UNITED STATES PATENT OFFICE.

ANDREW P. TRUCKSESS, OF CAMDEN, NEW JERSEY.

SIGN.

Application filed September 5, 1922. Serial No. 586,099.

To all whom it may concern:

Be it known that I, ANDREW P. TRUCKSESS, a citizen of the United States, residing at Camden, in the county of Camden and State 5 of New Jersey, have invented new and useful Improvements in Signs.

The herein described device relates to new and useful improvements in signs of an illuminated nature and more particularly to 10 that class of sign in which the letter plates are perforated to show such letter, and the plates of a removable nature.

The primary object of the invention is to provide a sign of the type specified which 15 will be extremely simple in construction, of low cost to manufacture, durable in use, no hinged parts, no complicated parts, which feature will enable anyone to properly insert or remove the letter plates without difficulty.

Another object of the invention is to provide a sign which shall contain two or more rows of letters, which, owing to the construction of the device, appear to be on the same 25 plane, while in reality the lower row, or rows, extend beyond those above, the rows being so constructed as to enable anyone to readily remove or adjust one or more of the letters without disturbing others in the same 30 row or those in other rows, as no hinged parts are used in the device.

While the foregoing explains the general purpose and objects of the device, other objects and advantages will appear in the 35 specifications that follow, in which the novel features, construction and arrangement of the various parts will be brought out, described and claimed.

In the accompanying drawings, forming 40 a part of this specification, and in which corresponding parts are denoted by like designating numerals is illustrated the preferred form of the embodiments of the invention capable of carrying the same into 45 practical operation, it being understood that the invention is not necessarily limited thereto, as various changes in shape, proportions and general assemblage of the various parts may be resorted to without departing from 50 the principle of the invention or sacrificing any of its parts or advantages, in which: Figure 1 is a partial front view; Figure 2 is a view of one of the letter carriers; Figure 3 is a side view in section; Figure 4 is a 55 top view of a portion of the letter carrier in section.

To more fully describe the drawings, and to make clear the construction, operation and general purpose of the herein described device:—

The numeral 1 indicates a forwardly extending portion of the top, bottom, and side edges of the main sign body. A recess 2 is thus formed bounded by said forwardly extending portion. Within this recess is placed 60 the sign frame which is smaller than the recess and spaced on every side from the forwardly extending portion. Said framework of the sign consists of a closed back-wall which is secured against the front face 65 of the main sign body, a closed bottom wall, and closed side walls. The frame is divided off into two or more horizontal compartments by horizontal partitions 4, only two compartments being shown in the present 70 case. Each compartment is deeper and extends forward farther than the one above it. Vertical partitions 9 divide each compartment into chambers. The side walls and the 75 vertical partitions are provided with flanges 80 3. The top wall of one compartment is the bottom of the one next above it and is provided with openings along the front edges which extend the length of the above named 85 chambers. The front wall of the chambers is open, except as to the flanges 3. Through 90 these openings the letter plates 6 are displayed. The letter plates 6 are of wood or metal and have letters stenciled out of them. They are inserted through the openings near 95 the front edges of the top of the chambers and are displayed through the space between the flanges 3. Behind each letter plate is an opal glass plate, 7.

The letter plates and the glass plates in 95 the upper chambers rest upon the partition 4 and are spaced from its front edge the distance of the opening in said partition through which the letter plates and the plates 100 of the lower chamber are inserted.

Openings are also formed in the top of each chamber and behind that part of the top upon which the letter plates and the glass plates rest. These openings permit light 105 from the upper row of lamps to enter the chamber and illuminate the sign plates. If desired the front surface of the back wall may be polished or coated with white enamel so as to reflect the light against the sign plates.

Lamps 8 are placed all around the frame within the recess 2. Those along the sides

and at the bottom are mainly for ornamental purposes. Those at the top, however, serve to illuminate the sign plates.

It is to be understood that electric light 5 bulbs and attachments can be inserted in the back wall of the sign in each compartment for stronger illumination.

Having thus described my invention, what 10 I claim as new and desire to secure by Letters Patent, is:—

In a sign, forwardly extending top, bottom and side edges forming a recess in which 15 is located a sign frame spaced on every side from the forwardly extending portions, said framework of the sign consisting of a closed back wall, bottom wall and side walls, said frame being divided into horizontal com-

partments by horizontal partitions, each compartment deeper and extending forward farther than the one above it, chambers being 20 provided by vertical partitions which are provided with flanges at their front as well as the side walls, the top wall of a compartment being the bottom of the next above it, and is provided with openings to admit 25 light, the letter plates and glass plates resting upon the horizontal partitions and being spaced from the front edge the distance of the openings through which the letter plates are inserted, and lamps in the recess between 30 the sign frame and the forwardly extending edges.

ANDREW P. TRUCKSESS.
